UNITED STATES PATENT OFFICE.

ANTHONY W. HOCKMAN, OF PARKERSBURG, WEST VIRGINIA.

DESIGN FOR A BUILDING-BLOCK.

SPECIFICATION forming part of Design No. 35,120, dated September 17, 1901.

Application filed August 8, 1901. Serial No. 71,413. Term of patent 14 years.

To all whom it may concern:

Be it known that I, ANTHONY W. HOCKMAN, a citizen of the United States, residing at Parkersburg, in the county of Wood and 5 State of West Virginia, have invented and produced a new and original Design for Building-Blocks; and I do hereby declare the following to be a full, clear, and exact description of the same, reference being had to the accompanying drawings, forming a part thereof.

This invention relates to a new and original design for building-blocks; and it is embodied in the configuration, shape, and particular formation of a block presently to be described, 10 and shown in the accompanying drawings.

The design is shown in the drawings in end view, Figure 1, and in top plan view, Fig. 2.

The design consists, essentially, in a rectangular body portion A, having a sloping or 15 inclined front face B, terminating at its upper edge in a rib or projecting flange C, which extends the entire length of the block. The sloping face portion of the block extends longitudinally beyond the ends of the body A, 20 as shown in Fig. 2.

The under face of the block is channeled, as at D, a portion of the channel being in the front part and a portion in the body part of the block, as shown in Fig. 1.

The essential feature of the design is the 30 body portion having the inclined front-face portion extending above the plane of the body portion.

While I have stated that the invention relates to a new and original design for building-blocks, it is to be understood that by the term "block" I intend to include such structures as composite building-blocks, bricks, terra-cotta, and blocks of other material. 35

Having thus described the invention, what 40 I claim as new, and desire to secure by Letters Patent, is—

The design for a building-block substantially as described.

In testimony whereof I affix my signature 45 in presence of two witnesses.

ANTHONY W. HOCKMAN.
